UNITED STATES PATENT OFFICE.

HERBERT F. OBERGFELL, OF RIVER FOREST, ILLINOIS, ASSIGNOR, BY MESNE ASSIGNMENTS, TO AUTOMATIC ELECTRIC INC., OF CHICAGO, ILLINOIS, A CORPORATION OF DELAWARE.

CALLING DEVICE.

Application filed May 15, 1924. Serial No. 713,378.

The present invention relates in general to calling devices, and more particularly to impulse senders for automatic telephone systems in which the selector switches used for building up a connection are directive-
ly controlled by current impulses sent from a subscriber's station; and the object of the invention is to produce an improved mechanism of this character embodying a number of novel features tending to increase its efficiency and enhance its usefulness in practice.

The invention is illustrated in the accompanying drawings, comprising Figs. 1 to 8, inclusive, which are described below:

Fig. 1 is a projected view of different parts of the calling device showing their relation to each other.

Fig. 2 is a front view of the device complete.

Fig. 3 is a rear view of Fig. 2.

Figs. 4 to 8, inclusive, show various parts of the device, Figs. 6 and 7 being shown double size and in cross section.

The calling device consists of a cup-shaped frame member 25, which supports the various mechanisms of the device, including the usual finger hole dial which is operated by means of finger holes 64 distributed around its periphery.

In the construction of the device a spring member 63 having a hole in the mid point thereof for receiving a reduced portion of the hub 27, is placed within the cup 25 in the position shown in Fig. 1. A reduced portion of hub 27, shown in Fig. 7, extends through the opening in spring 63, and through a similar opening in the base of the cup and is firmly staked in place.

A power spring holding member 42 (see Figs. 3 and 7) slides over the reduced portion of hub 27 and is fastened to the cup 25 by means of ears 43 and 43', which extend through the base of the cup and through openings in spring 63, these ears being bent over as shown in Figs. 1 and 7. By this means spring member 63 is further secured in place.

Referring now to Figs. 3 and 6, an arched bracket 57 is staked to the bottom side of

the cup member 25. This arched bracket provides a bearing for shaft 59 and also serves as a supporting means for the governor shaft bearing.

Returning now to Fig. 1, a unit comprising pinion 70 and worm wheel 71 is in fixed relation on shaft 59. This unit is inserted in place in the device through an opening in the base of member 25, the lower end of shaft 59 extending down through an opening in bracket 57, as illustrated in Fig. 6. A bracket 44 placed within the cup has an extension which serves as a bearing for the upper end of shaft 59. This bracket has two bosses 49 and 50 which definitely determine its location with respect to the cup member 25 and is held in place by screws 32 and 32'.

A fiber washer 58, and a gear and ratchet unit 22 comprising ratchet wheel 23 and gear wheel 24 are placed on the hub 27. The thickness of washer 58, the height of hub 27, and the thickness of unit 22 are such that with the unit 22 in place the top of hub 27 is not quite flush with the top of the unit. A fiber washer 21 fits snugly over a large part of shaft 20, as illustrated in Fig. 4. When the shaft 20 and its associated plate 18, to which shaft 20 is staked, are put in place, shaft 20 extends down through and beyond the opening of hub 27.

When the above described units are in place, gear wheel 24 meshes with pinion 70 and pawl 35, mounted on the under side of plate 18, engages a tooth of the ratchet 23. It will be noted from this that the unit 22 will be frictionally engaged between washers 58 and 21.

Plate 18 is provided with an arm forming stops 72 and 73, and when this plate is in its normal position stop 72 engages a fixed stop 33 which is a part of bracket 44. The rotation of plate 18 in a clockwise direction is limited by the stop 73 engaging the opposite side of fixed stop 33.

The number dial 15 fits in the ledge surrounding the upper portion of member 25, and the tip or bent over ends 26 and 26' of spring member 63 snap over the shoulder 81 of number dial 15 to hold the same in

place. The bracket 44, as illustrated in Fig. 1, has an extended portion 29 which extends upward through a notch 74 in dial 15 and is formed into a finger stop 11.

- 5 In certain cases for reasons which will subsequently be described, a bracket, such as bracket 44' Fig. 8, is substituted for the bracket 44, in which case the arm such as 29 is cut off instead of arm 29' as shown in 10 Fig. 1, the arm similar to 29' terminating in a finger stop 11'. In such a case notch 75 of number dial 15 is the one through which the part forming a finger stop passes.

A keyed portion 62 on plate 18 is for receiving a similarly shaped keyed opening in the center of finger hole dial 10, which is held in fixed relation to the plate 18 by machine screw 9.

An instruction card holding ring 1 is provided with three ears, 2, 3 and 3', respectively, which permit this ring to be snapped in place on the dial 10 in openings in the dial provided for this purpose. Before putting the ring in place, a celluloid disk 5, 25 and an instruction card 7, provided with notches 6 and 8, respectively, are placed within the ring. The ring 1 is provided with an ear 4 in all respects the same as ears 2, 3, and 3', except that it is bent the opposite way. This ear definitely determines the position of disks 5 and 7.

Referring now to Figs. 3 and 6, a nut 56 having a shoulder is screwed down on the shaft 59 and an impulse cam 55 is positioned on the shoulder of the nut 56, the cam 55 being held in place by a washer 60 and a nut 61.

The governor 76 is of the well known worm driven type and is supported at one 40 end by a portion of bracket 57, and at the other end by a bearing supported by a cut out portion of the cup member 25 bent at right angles thereto.

A spring assembly having fixed to it a member provided with arms 51 and 53 is placed on the shaft 20, one end of the spring 82 of the assembly being fixed to the shaft and the other end being fixed to a notch on the previously described member 42. 45 This spring assembly is substantially the same as that shown and described in a pending application of Obergfell, Serial No. 679,517, filed December 10, 1923. When one end of the spring 82 is secured to a notch in member 42 the same is rotated at least one revolution before fixing the other end to shaft 20 which is the usual practice in the assembly of this type of calling device. The tension of spring 82 tends to 50 rotate the plate 18 in a counter-clockwise direction, which rotation is prevented as previously explained by stop 72 engaging stop 33, and also causes the spring to normally tend to hold the unit 22 and washers

21 and 58 into frictional engagement with each other between member 25 and plate 18 for a purpose which will later be explained.

A bracket 80, carrying impulse and shunt spring assemblies, and also provided with a pair of lugs 48 and 48' for securing the dial in a telephone, is held in place on the base of member 25 by machine screws 47 and 47', respectively. When this assembly is in place shunt springs 36, 37 and 38 normally tending to engage each other are prevented from doing so by the cam like arm 51. Impulse springs 40 and 41, which are tensioned to normally extend within range of the impulse cam 55, are held out of range of this cam by the arm 53 engaging a bushing on the impulse spring 40. A back stop spring 41 determines the normal position of springs 39 and 40 when the arm 53 is moved away from the bushing on spring 40. In Fig. 3 the spring 41 has been broken away to more clearly show the relation between arm 53 and spring 40, spring 41 being shown in its entirety in Fig. 5.

It will be noted from observation of Fig. 3 that each shunt and each impulse spring has adjacent it a washer provided with a screw terminal which permits connections to be made with the aid of a screwdriver.

Also since the bracket 80 is fastened to member 25, by the simple removal of screws 47 and 47', the calling device less its impulse and shunt springs may be readily removed for repair, etc.

Operation.

Upon the forward rotation of dial 10 plate 18 and shaft 20 are rotated and additional power is stored in power spring 82. At the beginning of the forward movement of the dial arms 51 and 53, being in fixed relation with the shaft 20, move away from the associated bushings permitting the shunt springs to engage each other and also permitting the impulse springs to come within range of the impulse cam. During the forward motion of the dial no part of the gear train is affected, because of the pawl and ratchet connection between plate 18 and the unit 22. When the dial is released the unit 22 is rotated with it and since gear 24 is in mesh with the pinion 70, this pinion, worm wheel 71, and the governor 76 are operated, the governor acting in the usual capacity of maintaining the rate of operation of the mechanism at a uniform speed, and the impulse cam serving the usual purpose of opening the line circuit extending through the impulse springs 39 and 40 a number of times determined by the number of the digit dialled.

At the beginning of the last half revolution of the impulse cam 55, arm 53 again engages the bushing associated with impulse

spring 40 and arm 51 again engages the bushing associated with shunt spring 38. During this last half revolution of the impulse cam and just prior to the time cam 55 would ordinarily again operate the impulse springs, cam 53 moves them out of range of the cam 55 rendering its last half revolution ineffective. Just before the stop 72 on plate 18 engages the stop 33 the end 10 of pawl 35, to which spring 19 is attached, engages an arm 30. This arm has a certain amount of resiliency and prevents the sudden jar which would otherwise result if the stopping action were dependent solely on 15 stops 73 and 33.

Under certain conditions it may be desirable to use the calling device without incorporating the delay feature. This may be readily accomplished by simply substituting 20 the bracket 44' (Fig. 8) for the bracket 44, and by rendering the means for moving the impulse springs out of range of cam 55 ineffective. This may be readily accomplished in any of several ways, for instance, 25 a spring unit having only an arm 51 may be substituted, arm 53 may be cut off, or a spring such as 40 without a bushing may be used.

When bracket 44' is used its finger stop 30 11' is located midway between the designations 1 and 0. This permits the dial to be only operated sufficient distance to rotate the impulse cam five revolutions, causing the transmission of ten impulses. It will, 35 therefore, be seen why the impulse springs 40 and 41 must continuously remain within range of the impulse cam when no delay is desired.

In certain instances it is necessary to 40 change number dials. Since the finger hole dial of the present calling device may be put in place and removed without the necessity of removing the shaft 20, the removal and substitution of number dials is made 45 relatively simple, and is accomplished without affecting the adjustment of the operating mechanism.

In calling devices of the ratchet type such 50 as disclosed by Keith, Patent No. 1,209,303, reissued December 19, 1916, a hub similar to hub 27 supports a gear and ratchet unit. In the calling device of the patent the hub 27 extends through the unit, which is only 55 connected to the dial by the usual driving pawl. In the patent the normal position of the dial is determined by a pin on the dial engaging a tooth of a pinion similar to pinion 70. Now in operating the dial in a careless manner it sometimes occurs that, 60 since the ratchet and gear unit are free to rotate while the dial is in an off normal position, sufficient momentum is set up in the unit to cause it to advance slightly and when the dial reaches normal it engages a 65 tooth of the pinion even though the pawl

on the dial is setting midway between two teeth of the ratchet wheel. When this occurs the impulse cam will hold the impulse springs open although the dial is at normal. If the device is left in this condition and a subscriber attempts to make another call the calling device springs will be closed responsive to dialling the digit one or will be closed and then opened once only if the digit two is dialled, etc.

In the past this above trouble has been overcome to a degree by tensioning the pawl spring, associated with the dial, very stiffly, which resulted in noisiness of operation and increased friction between the bottom 75 side of the gear unit and the dial supporting frame. In order to overcome the increased friction between the unit and the frame the power spring had to be tensioned more stiffly. The result was a dial which 80 operated not only noisily but stiffly.

In the present calling device, as previously pointed out, the hub 27 does not extend quite through the unit 22, and therefore the power spring 82 in holding the shaft 20 85 and the associated plate in place also holds the unit 22 in frictional engagement with plate 18 and member 25 through the medium of the fiber washers 21 and 58, and any tendency of the unit 22 to run ahead is overcome.

Due to the large surface covered by washers 21 and 58 the tension between plate 18 and member 25 need not be very great. Furthermore, since the pawl 35 does not enter into this frictional arrangement its 90 spring may be of very light tension, resulting in quietness of operation. These arrangements make it practical to maintain the normal tension of power spring 82 at 95 a minimum which is reflected by the easy operation of the dial.

The various features and advantages of the invention having been described and ascertained, what is considered new and is 100 desired to have protected by Letters Patent will be pointed out in the appended claims.

What is claimed is:

1. In an impulse sending device, a finger hole dial, a supporting shaft for said dial, an impulse mechanism for said device including a train of gears for operating it, a source of power for operating said train of gears comprising a spring normally tending to rotate said dial, a stop for normally preventing its rotation, a number dial located between said finger hole dial and said mechanism, means for holding said dial in place, and means for removing said number and finger hole dials from said device while retaining said mechanism, gears, shaft, dial holding means and spring intact.

2. In an impulse transmitting device, a cam, impulse springs, an impulse cam driving pinion, a gear for driving said pinion, a

- rotatable dial, a ratchet connection between said dial and driving gear, a power spring for operating said gear and pinion to rotate said cam, means for storing power in said 5 spring, and means including fiber washers for maintaining a frictional connection between said dial and said gear at all times to prevent any possible over run of said gear and cam.
- 10 3. In an impulse transmitting device, a supporting shell, a number dial, and means fixed to said shell for securing said dial thereto, said means comprising a spring member having a hook at each of its extreme ends which snap in place over the edge of the dial when the dial is properly positioned on said shell.
- 15 4. In an impulse transmitting device, a rotatable finger hole dial, a finger stop for limiting the distance of rotation of said dial, and a second finger stop which may be substituted for said first stop to increase the possible distance of rotation of the dial.
- 20 5. In a calling device, a pair of interchangeable finger stops, a rotatable finger hole dial rotatable different maximum distances dependent on the stop used, an impulse cam, and mechanism controlled by the angular displacement of said dial for rotating said cam a maximum of five or five 25 and one-half revolutions depending on the finger stop used.
- 25 6. In a calling device, impulse sending mechanism, a finger hole dial having a pawl thereon, a pinion for driving said mechanism, a shaft, a unit consisting of a gear and a ratchet wheel loosely mounted on said shaft for communicating the operation of the finger dial to said pinion, and 30 means for clamping said unit between frictional surfaces in assembling the device to prevent the unit over running the pawl.
- 35 7. In a calling device, impulse sending mechanism, a pinion for driving said mechanism, a finger dial, a plate upon which the device is assembled, a shaft and a pawl on the dial, a stud on the plate having a hole therein for receiving said shaft, a unit gear and ratchet wheel mounted on said stud 40 and rotatable thereon by means of said pawl to communicate the operation of the dial to the mechanism, said stud being shorter than the unit, and a pair of frictional washers 45 above and below the unit and clamped against the same to prevent free rotary movement thereof.
- 50 8. In a calling device, a finger hole dial, impulse sending mechanism, a gear and ratchet train for operating said mechanism, a unit consisting of a shaft carrying a plate at one end, forming a stop to limit the rotary movement of the dial and having a pawl mounted on said plate to communicate the rotation of the shaft to said ratchet 55 and gear train, projections on the other end of said shaft for rendering said impulse mechanism inoperative, and means for mounting said finger dial on one end of said shaft so that the shaft may be rotated by the dial.
- 59 9. In a calling device, a rotatable impulse cam, a finger hole dial, mechanism controlled by said dial for transmitting rotary movement to said cam, interchangeable finger stops limiting the distance of rotation of the dial and thereby limiting the number of revolutions of said cam, one of said stops permitting the dial to cause the cam to rotate a definite maximum number of revolutions, and the other stop permitting the dial to cause the cam to rotate a smaller maximum number of revolutions.
- 64 10. In a calling device, a finger hole dial, an impulse cam rotatable a number of revolutions dependent on the angular displacement of said dial, and interchangeable finger stops for said dial permitting the possible angular displacement of said dial to be varied.
- 69 11. In an impulse transmitting device, a driving element, a driven element, and means including fiber washers for maintaining a frictional connection between said elements at all times to prevent any possible over-run of said driven element.
- 74 12. In an impulse transmitting device, a driving element, a driven element, and means for maintaining a frictional connection between said elements at all times.
- 79 13. In a calling device, impulse mechanism, a rotatable element, a second element for driving said mechanism, a third element for communicating the operation of the first element to the second element, and frictional means for preventing the third element from over-running the first element.
- 84 14. In an impulse transmitting device, a cup shaped shell provided with a ledge at the top thereof, a number dial located upon said ledge, and flexible means secured to the base of said shell for holding said dial in place.
- 89 15. In an impulse transmitting device, a number dial, a finger hole dial, impulse and impulse operating mechanism for the device, means for holding the number dial in place secured to the device before the finger hole dial is put in place, and means for thereafter connecting the finger hole dial to the device.
- 94 16. In an impulse transmitting device, a number dial, a finger hole dial, a cup shaped supporting shell having a ledge in the upper edge of its wall for receiving said dial, and a spring member secured to the base of the shell provided with flexible extensions for firmly holding the dial in place.
- 99 17. In an impulse transmitting device, a supporting shell, a number dial, a spring member for holding the dial in place on

said shell, a power spring for transmitting motion, and means for holding both said springs in fixed relation to said shell.

18. In an impulse transmitting device, a cup shaped supporting shell, and a finger stop secured within said shell in fixed relation thereto.

19. In an impulse transmitting device, a main supporting shell, a finger hold dial, a

train of gears and impulse mechanism controlled by said dial and a finger stop within the shell for limiting the movement of the dial and also serving as a bearing for one of said gears.

In witness whereof, I hereunto subscribe my name this 10th day of May, A. D., 1924.

HERBERT F. OBERGFELL.
